ROTARY FLUID MOTOR

Earl G. Roggenburk, Cleveland, Ohio

Application September 17, 1952, Serial No. 309,980

2 Claims. (Cl. 121—34)

This invention relates to a new and improved rotary fluid pump or motor of the sliding vane type, and more particularly to an improved end seal for the housing within which the vanes rotate.

An object of my invention is to provide an improved rotary pump or motor wherein the improvement arises from a better sealing of the housing and from a better method of assembling the pump.

It is an object of my invention to eliminate all scoring of the end plate by the vanes and rotor of a rotary pump or motor, thereby to improve the life and efficiency of the rotary pump or motor.

A further object of my invention is to provide a sliding vane rotary pump or motor wherein close manufacturing tolerances do not have to be maintained on a large number of the pieces used to make the pump or motor, thereby to produce a less expensive tool.

It is another object of my invention to provide a sliding vane rotary pump or motor which is more efficient when new and whose efficiency over the life of the tool is maintained at a higher level than existing pumps or motors.

Another object of my invention is to make a compressed air-driven rotary pump or motor which uses less air, and to protect the bearings, thereby to greatly extend the life of the bearings.

At the present time many plants have fixed or semi-fixed facilities for producing compressed air. Only a limited number of pneumatic tools can be connected to the compressed air line. By providing a pneumatic tool which uses about 25 percent less air from the time it is manufactured until it is worn out, the user can connect 25 percent more tools to his compressed air supply.

For a better understanding of the present invention together with other and further objects thereof, reference is had to the following description taken in connection with the accompanying drawing and its scope will be pointed out in the appended claims.

Fig. 1 of the drawing is a graph showing the air consumption and the amount of air used per horsepower of the pump of the present invention compared to a prior art pump;

Fig. 2 is a sectional view showing the rotary pump; and

Fig. 3 is a sectional view taken along line 3—3 of Fig. 2.

With reference to the drawings, there is shown in Fig. 1 a graph having curves comparing the performance of the motor device of the present invention with the performance of a prior art device. There are three sets of data, each set of data being represented by two lines, and in each instance the dotted line shows the performance of the prior art device while the solid line shows the performance of the device of this invention.

The first pair of curves compares the horsepower output of the two motors and shows that the horsepower of the prior art motor drops off very rapidly when the motor is rotating above about 3333 R. P. M., whereas the horsepower of the present motor does not start to drop off rapidly until the rate of rotation of the motor reaches

2

about 4450 R. P. M. This shows that there is a wide range of high speed tool operation where the prior art device is practically worthless.

The second pair of curves shows the air consumption for the prior art and the new device. The prior art device uses considerably more air from zero R. P. M. up through 3700 R. P. M. Above about 3700 R. P. M. the new motor uses more air because it is capable of working hard in the upper speed range whereas the power output of the prior art motor has fallen to a point where it is incapable of doing effective work. In other words, at the speed where the old motor begins to use less air than the new motor, the horsepower output of the old motor is so low that it is not capable of effective use, whereas at that speed the new motor is in its most powerful range.

The third set of curves shows the air consumption per horsepower for the old and the new motors. This is a good measure of the efficiency of the two motors and shows from about 2000 R. P. M. to about 3650 (where 20 the old motor becomes valueless due to low power output) that the new motor is progressively more efficient than the old motor. At 2000 R. P. M. the old device uses about 40 percent more air per horsepower than the new one; at 3000 R. P. M. it uses about 50 percent more air per horsepower, and at 3650 it uses about 80 percent more air per horsepower.

The primary reasons for this outstanding decrease in the air consumption per horsepower and in the reduction in the total air consumed is the means for sealing the rotor 30 in the rotor housing, and the method of assembling the motor to assure a very small running clearance between the two end plates and the two ends of the rotor.

The details of the construction of the motor, or pump, are shown in Figs. 2 and 3.

35 The rotary motor is comprised of a housing 10 which preferably is generally cylindrical on the outside and comprises a forward section 11 and a rearward section 12 bolted together by four bolts 13 (only two of which are shown), extending through abutting flanges 14, 15 in the

40 two housing section 11, 12. The housing 10 is open in its interior defining a large cylindrical inner chamber.

A cylindrical liner 16 is positioned within the chamber in the housing 10 and the liner has a bore 17 which is eccentrically positioned with respect to the cylindrical 45 opening in the housing 10.

A shaft 20 extends into the inner chamber of the housing 10 and is eccentrically positioned with respect to the axis of the bore through the cylinder liner 16.

50 A rotor body 22 is integral with, or otherwise secured to, the shaft 20 and it has a plurality of slots 23 which extend in a direction parallel to the axis of the shaft 20 and radially with respect to the rotor. A sliding vane 24 is slidably positioned in each of the rotor slots 23 and as the rotor rotates, the outer end of each of the vanes 55 24 bears against the inner wall of the cylindrical housing liner 16 to effect a seal to substantially prevent the passage of fluid, such as air, between each vane and the inner surface of the cylindrical liner.

50 In order to support the rotor 22 and the shaft 20 with respect to the housing 10, there are provided two sets of bearing means, one at each end of the rotor. Each set of bearing means preferably comprises two ball bearing assemblies 30, 31, the inner races of which are pressed onto the shaft 20 and the outer races 33 of which 65 are pressed under the outwardly extending portion 35 of the end cap 36. Each end cap 36 is circular and its outer peripheral face 37 is in engagement with the inner face of the housing 10. A shoulder 38 on the front portion 11 of the housing 10 firmly holds the front end cap 36 in position, and the shoulder 39 on the rearward housing portion 12 similarly holds the back end cap 36 70 in position. The innermost edge 40 of each of the end

caps 36 abut against the end faces of the cylindrical liner 16 to center the liner and hold it in position within the housing 10.

Two end plates 45 are provided, one at each end of the rotor for sealing the two ends of the cylinder liner 16. Each end plate 45 is forced onto the shaft portion 20 of the rotor so that a positive seal is made between each end plate 45 and the shaft 20. This prevents any of the air which is driving the rotor from escaping between the end plates 45 and the shaft 20 and protects both of the end bearings 30, 31 from moisture and sludge carried by the air which drives the rotor. Each of the end plates 45 has a close running fit with an end wall of the cylindrical liner 16 to form substantially an air-tight seal to prevent the escape of the driving air and the sludge it carries with it into the location of the end bearings, thereby to greatly prolong the life of the end bearings, and consequently, since it is usually the end bearings which wear out first, to greatly prolong the life of the entire motor. The end plates 45 rotate with the shaft 20 and with the rotor 22 and rotor blades 24. Thus there is no relative rotary motion between the rotor blades and the end plates. This greatly improves the length and quality of the air seal between the rotor blades and the end of the cylinder.

In the prior art the rotor blades rotated with respect to the ends of the cylinder and as they were in frictional engagement with the cylinder ends to effect the required sealing engagement there was scoring of the cylinder ends and wear on the edges of the vanes. Also the rotor body would dig into the stationary end plates sometimes causing seizure between the parts. This rather quickly led to air leakage and reduced motor power. In the motor of this invention the end plates 45 form an effective air seal with the cylindrical liner along the sealing surfaces 50, 51, the sealing surface 50 being larger than the sealing surface 51 due to the eccentricity of the cylindrical liner with respect to the shaft 20 and the end plates 45. The fact that the sealing surface 50 is large is very valuable as it is near the air inlet port 52 where the air pressure is greater than it is at the outlet port 53, near the smaller sealing surface 51.

It is desirable to have the peripheral end surface 55 of each end plate 45 in close running relationship to the inner surface of the portion 37 of the end caps 36 to improve the air seal, though this is not critical and if the end plate is made slightly undersize during manufacturing it need not be scrapped. This is one of the savings in manufacturing cost which is brought about by the use of end plates 45 whose side faces seal with the end faces of the cylindrical liner 16.

The construction described is particularly useful in air motors, though other fluids may be used to drive the rotor. One of the problems faced by users of pneumatic motors is the moisture always present in the compressed air. This moisture is introduced into the pneumatic tool and carries with it dirt, etc., which forms a wet sludge which interferes with the free running of the tool and causes rusting of bearings, gears, etc.

The construction shown in Figs. 2 and 3 gives the greatest protection to the bearings and causes almost all of the moisture and sludge to go out of the regular exhaust port 53 without contacting the bearings. There is of course a slight leakage of air around the end plates 45. So long as there is a running fit with a differential air pressure on either side of the running fit there is bound to be some leakage. In order that this leakage will cause the minimum of trouble the motor is provided with two escape ports 60, one adjacent the peripheral edge of each of the end plates 45 and located on the side of the plates 45 away from the rotor 22. Any moisture or sludge which gets past the air seal between the inner face of the end plate 45 and the end face of the cylindrical liner 16 tends to fall to the lower portion of the motor where the escape ports 60 are located. Centrifugal force act-

ing on the moisture and sludge also tends to throw the moisture and sludge toward the escape ports 60 where it passes out of the tool. This helps to protect the bearings which are positioned inwardly on the shaft 20.

The air which drives the rotor 22 enters the motor at the rear end 61 and travels under pressure through chamber 62, through valve opening 63 and passageway 64 to the inlet port 52 into the rotor chamber where it expands and drives the rotor with its interconnected drive shaft 20 and the exhaust air then flows out through the exhaust port 53. If the motor tends to run too fast the centrifugal force throws the weights 65 outwardly with a pivoting action causing the plunger 66 to move the valve 67 to shut the valve opening 63 and reduce the air supply to the motor.

An important feature of the invention is the method of assembling the motor to obtain the close running fits which permit the rotor to run freely yet keep the air leakage to a minimum. The rotor 22 is made about .002 inch longer than the cylindrical liner 16. Two identical end assemblies are connected to the rotor shaft 20. Each end assembly comprises two ball bearing devices 30, 31 which fit around the shaft 20 with a shim 70 about .001 inch thick located between the inner ball bearing 30 and the end plate 45. The governor mechanism serves as a bearing lock nut at one end and a lock nut is provided at the other end to hold the bearings in place. An adjusting cap 71 is threaded over the outwardly extending portion 35 and is in engagement with the ball bearing 31. Each adjusting cap 71 is turned until the inner face 45' of each end plate 45 is flush with the outer edge 36' of the end cap 36. The sub-assembly comprising the rotor 22, rotor shaft 20, cylindrical liner 16 and the two end assemblies is then inserted into the housing section 11. When the housing section 12 is then bolted to the housing section 11 by means of the bolts 13, running clearance of about .001 inch is automatically provided along edges 40 between the end plates 45 and the ends of the cylindrical housing. If any adjustment is necessary it is a relatively simple matter to unbolt the two housing sections 11 and 12, remove the sub-assembly and either tighten or loosen either of the two adjusting caps 71, and to then replace the sub-assembly. The running clearance is obtained by slight shifting of each of the bearing means so that a distance of about one-half of the difference in length between the rotor and the cylinder liner is provided between the cylinder liner and the sealing face of the rotating end plates.

While there have been described what are at present considered to be the preferred embodiments of this invention, it will be obvious to those skilled in the art that various changes and modifications may be made therein without departing from the invention, and it is, therefore aimed in the appended claims to cover all such changes and modifications as fall within the true spirit and scope of the invention.

What is claimed is:

1. In a rotary motor; a cylindrical housing; a cylindrical liner shorter in length than said cylindrical housing and having end sealing surface means positioned within said housing, said liner having a bore eccentrically positioned with respect to said housing; a rotor having radially extending slots mounted within said housing and having a shaft portion of diameter smaller than said rotor; vanes slidably mounted within said slots for sealing engagement with the inner wall of said cylindrical liner as said rotor rotates with respect to said housing; bearing means mounted between said housing and said shaft portion for rotatably supporting said rotor with respect to said housing; a circular end plate mounted around and in close frictional relationship to said shaft portion of said rotor at a location between said bearing means and said vanes for rotating with said rotor and having one of its faces in close running overlapping relationship to the

said end sealing surface means of said cylinder liner for sealing the end of said housing; and an end cap mounted between said housing and said bearing means, said end cap having a tubular threaded portion around said bearing means; and a threaded adjusting nut on the threaded portion of said end cap and in engagement with said bearing means for adjusting the axial loading on said bearing means and thereby to adjust the axial force between said bearing means and said end plate.

2. A rotary motor as set forth in claim 1, further characterized by two such end caps and threaded adjusting nuts, one at each end of said rotor.
